CLAIM

The ornamental design for a display screen with graphical user interface, as shown and described.

DESCRIPTION

The patent or application file contains at least one drawing executed in color. Copies of this patent or patent application with color drawings(s) will be provided by the Office upon request and payment of the necessary fee.

FIG. 1 is a front view of a display screen with graphical user interface showing our new design; and,

FIG. 2 is an enlarged view of the claimed design shown in FIG. 1.

The broken line showing of the remainder of the graphical user interface and display screen is for environmental purposes only and forms no part of the claimed design.
